United States Patent Office.

FREDERICK M. RUSCHHAUPT, OF NEW YORK, N. Y.

Letters Patent No. 79,010, dated June 16, 1868; antedated June 4, 1868.

IMPROVED EXPLOSIVE POWDER.

The Schedule referred to in these Letters Patent and making part of the same.

TO ALL WHOM IT MAY CONCERN:

Be it known that I, FREDERICK M. RUSCHHAUPT, of the city, county, and State of New York, have invented a new and improved Explosive Powder; and I do hereby declare that the following is a full and exact description thereof.

The nature of my invention consists in the production of an exploding-powder, which will produce the required effect by percussion or proper friction, without using dangerous, poisonous, or corrosive substances, as fulminate of mercury, phosphorus, sulphur, &c., &c., and which allows of being handled and worked with during the preparation, transporting, or storing of it, without the slightest danger whatsoever.

The many substances which have hitherto been used for percussion or friction-powders, are either of a dangerous, explosive, and poisonous nature, or they are highly corrosive and liable to decomposition, or composed of expensive materials, &c., &c. It is therefore natural that objections have been and will be made against their general practical use. It will not be necessary for me to enter here into a detailed description of such substances, as also not to give detailed proofs about the mentioned objections against them, and their application for the purpose set forth.

The public in general is fully aware of their great danger during handling, &c. Many terrible accidents, more or less unpreventable, and not to be before seen, have occurred, and have written the true character of these powders with glowing letters into the annals of daily life. But the danger combined with the handling and use of these powders, is not only caused by an unpreventable explosion; their particularly poisonous character adds just as much to it, and is another reason to be fearful, and, consequently, to do entirely away with them. Persons who have been engaged in preparing or mixing the ingredients of these powders, are commonly, after a short time, affected on their hands, noses, or eyes, &c., with sores; they become injured on their lungs, and are lastly wholly poisoned; they die, or are ruined in health for lifetime.

Other explosives, being free of poisonous ingredients, are nevertheless dangerous to be handled. They altogether will explode by a sudden rise of temperature, and a single spark of fire, however small it may be, will give rise to a most fearful detonation. They are otherwise of a more or less corrosive nature, so that the metals, particularly of the pistons on the pistols and guns, &c., with which they come into contact, will soon be corroded, and a breaking will finally be the result of it. Some explosives being of less danger during handling, and also of a less corrosive nature, as, for example, a mixture of chlorate of potassa and tannin, &c., bear a proportionally high price, and the ingredients of them are otherwise used for most important technical purposes. In regard of true economy, they are, therefore, to be substituted by other suitable and less important substances.

To avoid all the before-mentioned objections, and to produce a most economical compound, which will surely explode, and answer the purpose required by percussion or proper friction, is the object of my invention, which consists in the use of a mixture of chlorate of potassa, or any other similar oxidizing-agent, and "naphthaline."

These mixtures are made in accordance with the laws of chemical affinity and stoichiometry. They detonate easy and sure, by percussion and proper friction, producing a most perfect combustion, accompanied with a light flame. They leave very little residue, and the gases thus produced are free of injurious properties, free of smoke, of an agreeable flavor, and consist of carbonic acid and water. They are not remarkably affected by dampness, and in consequence of the constant constitution of their components, no decomposition can take place.

These mixtures will not explode by fire, or the electric spark, &c., nor by sulphuric or any other acid which may come into contact with them.

The naphthaline of the compound will be ignited only; it will burn with smoke, just as it will do alone, not being in admixture, and the fire thus produced can easily be extinguished, without any danger whatsoever.

The naphthaline can be bought in any quantity for a very low price, from two to five cents per pound. It has as yet not found any other practical use, and experiments which have been made with it, to produce colors

from it, which might substitute those manufactured from aniline, have not only proved to be unsuccessful, but to be of no value at all.

In using this substance, of which the coal and wood-tars contain so abundant quantities, (and which is always obtained in the respective manufactures as a secondary product,) for the production of an explosive compound, I make a most economical as well as useful application of it, which otherwise has proved to be only a burden for the respective manufacturers.

To enable others skilled in the art to make and use my invention, I will now proceed to describe the *modus operandi*.

I take about seventy-five parts of well-powdered pure chlorate of potassa, and twenty-five parts of naphthaline, previously purified, by pressing and sublimation, of all tar-oils, pulverize it, and mix both on a smooth sheet of paper with a wooden knife.

In order to prevent the mixture from dusting, and to make it fit for adhering in the caps, cartridges, &c., I add then from four to five per cent. of a compound varnish to it, consisting of a fluid solution of gum-shellac in alcohol, and Damar in turpentine. Three-fifths of the first and two-fifths of the latter will be a suitable proportion. The powder dries in a short time, and is then ready to be filled in the caps, cartridges, &c., in the common way. In some respects it may be well to substitute a part of the chlorate of potassa, by an equivalent amount of saltpetre or another similar oxidizing-agent, or to mix from three to seven per cent. of powdered prussiate of potassa with it. Thus the price can be reduced. But it must hereby not be forgotten that the residue after combustion will be somewhat increased.

Having now fully described my invention, I wish it distinctly understood that I do not claim the already-described and used fulminates, nor do I claim the use of chlorate of potassa or any other oxidizing-agent; but

What I claim for me as new, and desire to secure by Letters Patent, is—

The use of "naphthaline," in a manner as described, and for the purpose set forth.

FREDERICK M. RUSCHHAUPT.
